[57] CLAIM

The ornamental design for a refrigerated display case, as shown and described.

DESCRIPTION

FIG. 1 is a perspective view of a refrigerated display case showing my new design;

FIG. 2 is a front elevational view thereof;

FIG. 3 is a rear elevational view thereof;

FIG. 4 is an end elevational view of one end thereof; FIG. 5 is an end elevational view of the opposite end shown in FIG. 4;

FIG. 6 is a top plan view thereof;

FIG. 7 is a bottom plan view thereof;

FIG. 8 is a front elevational view of a second embodiment of that shown in FIG. 1;

FIG. 9 is a rear elevational view of the second embodiment;

FIG. 10 is a top plan view of the second embodiment;

FIG. 11 is a bottom plan view of the second embodiment; and,

FIG. 12 is an end elevational view of the second embodiment, the opposite end view of which is a mirror image thereof.
